UNITED STATES PATENT OFFICE

OSCAR VAN DER STEYN AND DAVID LYONS, OF LOS ANGELES, CALIFORNIA

DESIGN FOR A GAME BOARD OR SIMILAR ARTICLE

Application filed December 10, 1932. Serial No. 46,427. Term of patent 3½ years.

To all whom it may concern:

Be it known, that we, OSCAR VAN DER STEYN and DAVID LYONS, citizens of the United States, whose business address is at 306 Civic Center Building, in the city and county of Los Angeles, State of California, have invented a new, original, and ornamental Design for a Game Board or Similar Article, of which the following is a specification, reference being had to the accompanying drawing, forming a part thereof.

Fig. 1 shows a plan view of a game board or similar article illustrating our new design, and Fig. 2 shows an end view thereof.

We claim:

The ornamental design for a game board or similar article as shown.

Dated this 28th day of November, 1932.

OSCAR VAN DER STEYN.
DAVID LYONS.
